METHOD OF AND APPARATUS FOR DRY CONCENTRATION

George W. Beach, Minneapolis, Minn.

Application March 3, 1938, Serial No. 193,702

7 Claims. (Cl. 209—477)

My invention relates to a method of, and apparatus for, separating and recovering precious and valuable metals such as gold, silver and the like from the sand, gravel or soil in which they are found in placer mining.

The primary object of the invention is to provide a method of separating valuable metals from the material in which it is found which employs air as the operating agent and which includes the blowing of the air over riffles and discharging the material into the air stream, and which further includes the withdrawal of a part of the air back before it reaches the riffles and the subsequent return of this air into the main air stream where it passes over the riffles to thus set up a turbulent, whirling action which will cause the heavier particles to settle behind the riffles while the lighter material is blown out.

A further and most important object of the invention is to provide an apparatus for this purpose in which the deposit containing the gold or other metal is fed into the path of an air blast which carries the deposit over a series of riffles so that the heavier metal will collect behind these riffles and the lighter material will be blown out and clear; and to provide also a separate air chamber into which a part of the air blast is directed and subsequently discharged downwardly into the main air blast to create the whirling, turbulent action over the riffles such as will cause the metallic particles to settle behind the riffles while the lighter particles of sand or soil will be blown outwardly from the machine thus leaving a concentrated collection of the valuable metal which may be removed and cleaned of any small impurities, if necessary, by washing. Another object is to provide a machine of this kind in which the riffles are arranged in a removable tray for convenient removal and cleaning and in which the riffles themselves are of serrated or saw-toothed design to facilitate their collecting action on the material blown thereover. A further object is to provide in a machine of this kind having a novel and effective feeding means for carrying the metal bearing deposit into the path of the air blast and which is so designed as to prevent clogging or over-feeding of the material and insure even distribution of the material over the entire riffle assembly. A further object is to provide a machine of this nature in which separate control means are employed to regulate the amount of air diverted from the air blast into the air chamber and the amount of this air admitted to the riffle chamber to mingle with the main air blast, thus making it possible to read-

ily accommodate the machine to use in material of any character.

Still a further important object is to provide a machine for this purpose in a simple, compact and portable form and which employs no working parts other than the blower and prime mover which provide the air blast for the operation of the machine.

The foregoing and other more detailed objects of the invention, together with means whereby they may be carried into effect, will best be understood from the following specification in which reference is made to the accompanying drawings, wherein:

Figure 1 is a side elevation of the complete machine as set up ready for use.

Figure 2 is an enlarged vertical and longitudinal section through the machine proper, only a portion of the feed hopper and the air blower being shown.

Figure 3 is a plan view of the structure shown in Figure 2, a portion of the machine being broken away to disclose interior construction.

Figure 4 is a fragmental horizontal section along the line 4—4 in Figure 2.

Figure 5 is a vertical cross section along the line 5—5 in Figure 2.

Referring now with more particularity to the drawings, my invention is seen to comprise two main units, the apparatus, or machine A and the power unit B.

The apparatus A comprises the riffle housing 6 which constitutes the base member of the machine and which is arranged for removable mounting in a base frame or stand 7 made up of legs 8 and braces 9 which support the machine at a convenient working height from the ground. The extended upper ends 8a of the legs 8 define crotches or seats for the reception of the riffle housing 6. This housing 6 is, as shown, of elongated flat form made up of sheet metal to provide the bottom 10, narrow upstanding sides or margins 11 and the top 12 all of which define and enclose the riffle chamber 13. The ends of this chamber are open as shown at 14 and 15 and the end 14 is hereinafter known as the intake end and the end 15 as the discharge or delivery end.

Surmounting the housing 6 is the upper air chamber housing 16 which extends from adjacent the intake end 14 over the greater part of the length of housing 6, this housing 16 having the side walls 17, the ends 18 and 19 and the top or cover 20 which define and enclose an air chamber 21. This chamber 21 is considerably

deeper or higher than the aforesaid rifle chamber 13 but is, of course, also considerably shorter.

Adjacent the intake end of the machine the cover 20 carries a hopper receptacle 22 made up of the outwardly and upwardly flared or inclined walls 23 adapted to receive and removably support the narrow lower end of the hopper 24. This hopper has a screen 25 onto which the soil or material is shoveled or deposited and through which it descends down into the machine.

A plurality of feed tubes 26 are extended down through the housing top 20 in transverse spacing within the hopper receptacle 22 and these tubes open at their upper ends, as at 27, so that the material fed from the hopper will enter the tubes. The feed may, however, be cut off to any tube and at any time by means of slideable cut-off valves 28 which lie flat on the housing top 20 and pass slidably through slots 29 in the wall 23 so that they may be moved inwardly over the mouths of the tubes. From their upper ends the tubes 26 incline downwardly and forwardly (away from the intake end of the machine) and drop through openings formed in the top 12 of the rifle housing 6 to thereby enter the rifle chamber 13 at a point spaced some distance from the intake end 14 thereof. The lower extremities of the feed tubes 26 are cut off angularly as at 30 to stand parallel to, but spaced some distance from, the housing bottom 10.

The rifle assembly or unit, designated generally at 31, comprises a tray or pan 32 of elongated rectilinear form adapted to be slipped endwise (through the delivery end 15) into the rifle chamber 13. This tray 32 has its lateral margins 33 turned upwardly to serve as guides and hold the tray in position in chamber 13 and the length and width is such that the tray will fit nicely into the chamber with one end slipped beneath the lower extremities of the feed tubes 26 and the other end extended some distance outwardly of the delivery end of the chamber to provide a hand hold for removing and replacing the tray. Spaced along the length of the tray 32 are a plurality of transversely extended riffles, rifle bars or cleats 34 which are inclined upwardly from the vertical in a direction away from the intake end 14 of the chamber 13. These riffles 34 are welded or otherwise secured in the tray 32, are of substantially less height than the chamber 13 and are serrated or saw-toothed along their upper margins as shown at 35. The function of these riffles and the advantages arising from their serrated construction will be hereinafter more fully set forth.

It will be noted that, with the rifle tray 32 in place, the lower or delivery ends of the feed tubes 26 clear the tray but a very slight distance and to permit the material from the hopper to feed down to the tray the frontal sides, or the sides remote from the intake end 14 of the chamber 13, are cut out from diametrically opposite points up to about the level of the upper wall of the chamber 13 as indicated at 36.

The machine as herein shown and described embodies three feed tubes 26 but it is to be understood that the machine may be made in any width, either greater or less, and may employ a corresponding number of the tubes. At points medially located between adjacent feed tubes the cover 12 of the rifle housing 6 is provided with air inlets or inlet openings 37 which are disposed inwardly of the adjacent end 18 of the housing 16 but immediately adjacent the intake end 14 of the chamber 13. Beneath each of these inlets

37 an inlet valve 38, of the so-called "flap" type, is located and is hinged at 38a to the underside of the cover 12 so that the free end of the valve may swing downwardly into the chamber 13 toward the intake end 14 thereof. A long screw 39 is pivotally attached at 39a to each valve 38 and extends upwardly through the housing cover 20 where it is provided with a wing nut 40 to thereby allow the valve to be adjusted in its position relative to its associated inlet 37. Therefore, when the wing nuts 40 are turned down on the screws 39, the valves 38 may be pulled upward to close the inlets 37, and vice versa. Normally the valves will stand slightly opened as shown in the drawings and will stand in adjusted position by force of gravity.

Forwardly of the feed tubes 26, or toward the delivery end of the machine, the housing cover 12 has several sets of parallel transverse rows of air return openings or apertures 41 and over each set or pair of these rows of openings an air return regulator or damper 42 is provided. These dampers 42, here shown as three in number, are attached at one margin to hinge rods 43 which extend through the sides 17 of the housing 16 immediately above the level of the cover 12 to pivotally support the dampers so that their free edges turn back toward the intake end of the machine. The dampers are of rectangular, flat shape of such length as to fit nicely between the housing side 17 and of such width that, in one position, they will close the adjacent air return openings 41 and, in another, they will stand upwardly against the housing top 20 to form a partition or air stop at that point. This positioning of the dampers 42 is carried out by means of handles 44 which are turned at right angles from one end of the rods 43 and play over the side of the housing 16 in engagement with toothed quadrants or racks 45 secured to said sides. Normally then dampers 42 will, like the valve 38, stand open to some degree as shown.

The foregoing assembly completes the machine itself and the power unit B will now be described. This comprises the base 46 supported on legs 47 and carrying a conventional form of air blower 48 having its outlet hood 49 flared to provide a wide mouth 50 of such shape that it may slidably enter the intake end 14 of the rifle chamber 13. The base 46 is supported at such height that it will allow the hood 49 to engage the machine A as described. A prime mover 51 of any kind is mounted also on the base 46 and drives the blower 48 through the belt 52 or equivalent means. Of course the type of prime mover used will depend upon the fuel or power available but, inasmuch as the machine will ordinarily be employed in relatively remote locations it is probable that a small gasoline engine will be employed as shown. In such case a pipe, such as 53, may be led from the engine exhaust to the blower intake in order that the air emitted from the blower 48 will be heated and will serve to dry out the materials fed to the machine A where such action is necessary.

The delivery end or mouth 50 of the blower hood 49 has air guides or fins 54 of V-shaped form located in line with the valves 38. The purpose of these guides 54 is to direct the air blast 70 from the blowers directly against the feed tubes 26 as will be evident and to thus distribute the feed evenly over the rifle tray. The guides 54 are welded at their bights 55 within the hood 49 but their wings 56 are left free so that they may

be compressed or spread apart as may be required to properly adjust the air distribution.

In operation the gravel or soil to be worked is, if necessary, screened to remove the larger pieces and then with the blower 48 in operation, the material is placed in the hopper 24 so that it enters the feed tubes 26 and is carried thereby down into the riffle chamber 13 and discharged onto the riffle tray 32. It will immediately be apparent that the blast of air entering the chamber 13 through its intake end 14 will blow the material forwardly over the riffle tray and the riffles 34 thereon and will spread the material evenly from the feed tubes 26 over the entire width of the tray. This action results from the novel arrangement of the delivery ends of the tubes 26 wherein the cut outs 36, located remote from the entrance of the air blast, allows the air to spread the material forwardly and laterally as it emerges from the tubes. Overfeeding and clogging is thus prevented and the location of the ends 30 of the tubes 26 immediately adjacent the riffle tray 32 presents an overhang or shield such as will prevent the material from being blown up the tubes by the air.

At the same time as the material is being blown forwardly over the riffles 34 a part of the air from the blower 48 is being deflected by the open valves 38 upwardly through the inlets 37 into the air chamber 21, and this air is then returned to the riffle chamber 13 at intervals along the length thereof through the air return openings 41. This air returning into the main air stream at an angle to the direction of travel thereof sets up a turbulent, swirling or whirling motion over the riffles 34 resulting in a like action on the part of the material such as will allow the particles of gold or other metal (which are heavier than the material itself) to settle behind the riffles 34 where they are protected from the air blast. The lighter material finally is blown out the discharge end 15 of the housing 6. This action is continuous so long as the blower operates and the material is fed to the hopper but the action may be stopped at any time by shutting off the blower and closing the slide valves 28.

As shown in the drawings the riffle housing 6, air chamber housing 16 and the riffle tray 32 taper somewhat in width and in a longitudinal direction and are accordingly somewhat narrower at the intake end of the apparatus. This formation has a twofold purpose. In the first place the material as it is spread by the air blast toward the discharge end of the machine has more space in which to move and the riffles themselves are longer so that the flow of material is substantially uniform over the entire area of the riffle assembly. Another advantage in this tapering arises from the ease with which the riffle tray 32 may be inserted into the riffle chamber 13 to provide a tight fit such as will prevent any of the material from working down beneath the tray.

The whirling, turbulent motion given the material by the returning of a part of the initial air blast to the main air stream over the riffles is an extremely important feature in that it allows much more of the finer metal to settle behind the riffles than would be the case where the air stream blown straight over the riffles. It is also important that the amount of air thus returned and used be regulated, at least roughly, according to the nature and quality of the material being handled and the valve 38 and the dampers 42 permit of such adjustment. In this

connection it may be pointed out that the dampers 42 may be adjusted to any relative positions to divert substantially equal quantities of the return air through the openings 41 or to divert greater quantities through certain openings as 5 may be required.

The machine or apparatus thus is seen to permit the practice of an entirely new and efficacious method of separating the heavier valuable metal from the material in which it is found, this 10 method comprising blowing an air blast over riffles, feeding the material into the air blast, diverting a part of the air before it reaches the feeding means and subsequently returning this air to the main air stream over the riffles to 15 thereby set up a turbulent swirling effect on the air and materials.

An important and advantageous feature of my invention lies in the fact that the method and the apparatus, using air as the agitating agent, 20 may be used in many arid locations where the wet methods and washers cannot be used. Another advantage is the ease with which the apparatus, at least in the small size herein shown, 25 may be taken down, carried from place to place and set up for operation at a new location.

The material collected behind the riffles 34 may be removed and, if necessary, further cleaned by washing, this action being readily carried out by removing the riffle tray 32. The serrated upper 30 margins 35 of the riffles permit the use of wider or higher riffles without unduly obstructing the separating action of the material and thus affords considerably greater effective area or surface for the riffles.

While I have herein set forth a certain preferred embodiment of my invention, it is understood that I may vary from the same in minor details, so long as such variations fall within the spirit and scope of the appended claims.

Having thus fully disclosed my invention, what I claim as new and desire to secure by Letters Patent is:

1. The method of separating valuable minerals from the natural deposit in which they are found, 45 which includes feeding the deposit onto a riffle surface, directing an air stream over the riffle surface to blow the deposit thereon, and diverting a part of the air stream upwardly prior to its meeting the deposit and subsequently returning 50 this diverted air downwardly to the main air stream to thereby set up a turbulence in the air stream carrying the deposit over the riffles.

2. The method of separating valuable minerals from the natural deposit in which they are found, 55 which comprises feeding the deposit onto a riffle surface, blowing an air stream over the riffle surface and in a direction crossing the riffles, diverting air from the air stream before it reaches the deposit and subsequently returning this diverted 60 air downwardly to the air stream at an angle to the direction of travel thereof to thereby set up a turbulence in the air over the riffle surface.

3. The method of agitating a natural deposit over a riffle surface to separate valuable metals therefrom, which comprises feeding the deposit adjacent the riffle surface, blowing an air stream across the riffle surface to carry the deposit thereover, and directing air downwardly into the path of this air stream over the riffle surface to cause 70 a turbulence in the air stream.

4. An apparatus for separating valuable metals from a natural deposit, comprising a housing having a chamber open at its opposite ends, means for directing an air stream through the 75

chamber from end to end thereof, riffle members located in the chamber transversely to the path of the air therethrough, deposit feeding devices entering the chamber adjacent the end at which the air stream enters, and an inlet means spaced along the length of the chamber over the riffle devices in parallelism therewith and effective to direct air streams into the chamber and downwardly into the path of the air passing therethrough.

5. An apparatus for separating valuable metals from a natural deposit, comprising a housing having a riffle chamber open at its opposite ends and an air chamber extended along the upper side of the riffle chamber but closed at its ends, an air supply means connected to one end of the riffle chamber to direct an air stream therethrough, an air inlet connecting the chambers adjacent this end of the riffle chamber, an air valve adjacent the said inlet and adjustable to divert a part of the air stream into the air chamber, feeding devices entering the riffle chamber inwardly of the said inlet, air return means connecting the chambers and spaced along the length and overhead of the riffle chamber, dampers arranged over the said air return means, and a riffle assembly mounted in the riffle chamber.

6. An apparatus for separating valuable metals from a natural deposit, comprising a housing hav-

ing a riffle chamber open at its ends, and an air chamber over the riffle chamber, means for feeding an air stream to one end of the riffle chamber, an air inlet connecting the two chambers adjacent this end, a flap valve arranged over the air inlet and adjustable into the path of the air stream entering the riffle chamber to thereby divert air into the air chamber, the said housing also having air return openings spaced along the length of the air chamber and communicating with the riffle chamber, damper plates adjustable over the said air return openings and adapted to divert air from the air chamber into the riffle chamber, deposit feeding means entering the riffle chamber between the said air inlet and the air return openings, and riffle devices in the riffle chamber.

7. An apparatus for separating valuable metals from a natural deposit comprising a riffle chamber open at opposite ends, blower means for directing an air stream endwise through the riffle chamber, feed means for feeding the deposit into the path of the air stream, riffle means in the bottom of the riffle chamber and opening upwardly and angularly in the direction of the air stream, and means for directing diverted air streams downwardly into the main air stream and toward the riffle means.

GEORGE W. BEACH.
